UNITED STATES PATENT OFFICE.

LAWRENCE FURLONG, OF HARTFORD, CONNECTICUT, ASSIGNOR TO FREDERICK C. ROCKWELL, OF SAME PLACE.

CLEAT FOR ELECTRIC WIRES.

SPECIFICATION forming part of Letters Patent No. 433,561, dated August 5, 1890.

Application filed February 18, 1889. Renewed July 9, 1890. Serial No. 358,121. (No model.)

To all whom it may concern:

Be it known that I, LAWRENCE FURLONG, of Hartford, in the county of Hartford and State of Connecticut, have invented a certain 5 new and useful Improvement in Cleats for Electric Wires, of which the following is a description, reference being had to the accompanying drawings, wherein—

Figure 1 is a side view of a cleat embodying my said improvement. Fig. 2 is an end view thereof. Fig. 3 is a view thereof in cross-section on the plane $x x$, Fig. 2.

The object and purpose of this improvement are the production of a novel and handy cleat 15 for attaching an electric wire to the ceiling or wall of a room or the like in a manner which will prevent the wire from having any lateral motion, but will not prevent from such longitudinal motion as necessarily results from 20 the expansion and contraction of the wire by varying degrees of heat and cold.

The letter a denotes one part of the cleat, and b denotes a screw for fastening the same to the ceiling of a room or the like. The letter c denotes the other part of the cleat. The part a is provided with projecting way-flanges $a' a'$, and the part c has corresponding way-grooves $c' c'$, which fit to and slide upon the way-flanges a' . These way-grooves are parallel with the line-socket. It will be readily understood that by means of these co-operating way-flanges and way-grooves the part c can be readily engaged with and disengaged from the part a . In and between these two

parts a and c is a line-socket d , formed one-half in each of these two parts. In the use of this device the part a is first affixed to the ceiling of a room or the like by means of the screw b , then the electric wire e is placed in that portion of the line-socket which is in the part a , and then the part c is engaged with the part a . This produces a fastening which is attachable to the ceiling of a room or the like by a single screw, which is susceptible of being made ornamental in appearance, because the part c covers up all the rest, by the use of which an electric wire can be put in place and removed at pleasure, which prevents the wire from having accidental lateral play, (a frequent source of conflagration,) but which permits the wire to have such small longitudinal motion as results from expansion and contraction of the wire through varying degrees of heat and cold without affecting the substantial integrity of the fastening.

I claim as my improvement—

In combination, the part a , provided with way-flanges $a' a'$ and line-socket d , parallel with the way-groove, the screw b , and the part c , provided with way-grooves $c' c'$ and line-socket d , all substantially as described, and for the purpose set forth.

LAWRENCE FURLONG.
